(57) **CLAIM**

The ornamental design for automobile tire, as show and described.

DESCRIPTION

FIG. 1 is a perspective view of an embodiment of an automobile tire showing my new design;

FIG. 2 is a front view thereof;

FIG. 3 is a back view thereof;

FIG. 4 is a left side view thereof, the right side being a mirror image;

FIG. 5 is a top plan view thereof, the bottom being an identical image;

FIG. 6 is a cross-sectional view along the lines 6—6 in FIG. 2; and,

FIG. 7 is an enlarged fragmentary plan view between the lines B and B in FIG. 2.
